SYNCHRONOUS-TYPE FLUID-BLAST CIRCUIT INTERRUPTERS HAVING SPACED NOZZLE-SHAPED CONTACTS

Fritz Kesselring, Zurich, Switzerland, assignor to Siemens-Schuckertwerke Aktiengesellschaft, Erlangen, Germany, a corporation of Germany
 Original application Mar. 27, 1961, Ser. No. 98,522, now Patent No. 3,215,804, dated Nov. 2, 1965. Divided and this application June 10, 1965, Ser. No. 462,936
 11 Claims. (Cl. 200—148)

This application is a divisional application of patent application filed March 27, 1961, Serial No. 98,522, now U.S. Patent 3,215,804, issued November 2, 1965, to Fritz Kesselring.

This invention relates to synchronous-type fluid-blast circuit interrupters in general and, more particularly, to improved interrupting structures therefor.

A general object of the present invention is to provide an improved synchronous-type fluid-blast circuit interrupter which will be highly efficient and which will utilize a minimum quantity of arc-extinguishing fluid.

Another object of the present invention is to provide an improved compressed-gas circuit interrupter in which the application of the arc-extinguishing medium is dependent upon a predetermined reduction in magnitude of the value of the instantaneous current being interrupted.

Still a further object of the present invention is the provision of improved compressed-gas circuit-interrupting structures in which more effective use of the gas-blast medium is obtained by the employment of synchronously-operated valve structures.

In United States patent application filed, March 22, 1961, Serial No. 97,656, now U.S. Patent 3,215,866, issued November 2, 1965 to Fritz Kesselring and Lutz Seguin and assigned to the assignee of the instant application, there are disclosed and claimed novel-type synchronous operators particularly suitable for synchronously-operated circuit-interrupting devices. It is a further object of the present invention to utilize the principles set forth in the aforesaid patent application rendering them highly efficient as applied to circuit-interrupting devices.

Additional objects and advantages will readily become apparent upon reading the following specification, taken in conjunction with the drawings, in which:

FIGS. 1 and 2 illustrate time graphs of energy input into circuit interrupters of conventional type and those embodying features of the present invention during the circuit-interrupting operation;

FIG. 3 is a somewhat diagrammatic view taken in vertical cross-section through a compressed-gas-type of circuit interrupter embodying features of the present invention, the contact structure being illustrated in the partially open-circuit position;

FIGS. 4-7 illustrate novel types of blast-valve arrangements embodying features of the present invention;

FIG. 8 illustrates a perspective view of a double-valve arrangement embodying features of the present invention;

FIG. 9 is a composite vertical sectional view taken through a compressed-gas circuit interrupter embodying features of the present invention, the left-hand portion, designated FIG. 9A, showing the closed-circuit position, and the right-hand portion, designated FIG. 9B, showing the open-circuit position;

FIG. 10 is a vertical sectional view taken through a modified type of compressed-gas circuit interrupter, the contact structure being illustrated in the closed-circuit position; and,

FIGS. 11 and 12 illustrate in vertical section and plan views, respectively, a modified type of orifice construction for the circuit interrupter of FIG. 10.

2

Referring to the drawings, and more particularly to FIGS. 1 and 2 thereof, it will be noted that the stresses exerted upon the interrupting chambers of electrical circuit interrupters are determined in accordance with their design by the maximum interrupting arc power or the maximum arc work dissipated. The latter case occurs when the pressure produced by the arc cannot be continuously equalized throughout the breaker, as it happens to be, for example, in oil circuit breakers. As it is known, the interrupting work A_s is given by the equation:

$$A_s = \int_0^{t_b} \mu_b i dt$$

where:

μ_b = instantaneous value of the arcing voltage,
 i = instantaneous value of the current, and
 t_b = arcing time.

It has been found that the mean value of the current i and, most importantly, the arcing time t can be reduced by control of synchronization. In single-phase circuit breakers the control of synchronization is applied in a relatively easy manner. On the other hand, in the case of polyphase circuit breakers, for frequencies of 50 or 60 cycles, considerable difficulties are often encountered. This fact can be seen at once in that the mass of the moving system necessary for large rated currents cannot be brought satisfactorily to the separated distance necessary for arc-extinguishing action in a sufficiently short time, for example, in .1 millisecond. Also, the current wave is not as singularly defined as in the case of single-phase circuit breakers. When, for example, a two-phase arcing short circuit changes shortly, before passage through current zero, into a three-phase short circuit, the current wave changes considerably, which may lead to faulty switching. Furthermore, the maintenance of so-called flashover interruptions under control presents considerable difficulties because of the then resulting extraordinary high arc power.

It is known that the value of the arc voltage depends very much on what kind of effect the quenching medium has upon the arc. If the arc is drawn in a still atmosphere, then the arc-voltage gradient is approximately 20 to 30 volts/centimeter. On the other hand, if the arc is subjected to, for example, intensive axial blasting, or, if in the gas-vapor atmosphere surrounding the arc under high pressure, there occurs a sudden expansion, then the arc-voltage gradient reaches 200 volts/centimeter, and more. In the case of the transition from little, or only slightly affected arcs, to strongly affected arcs, the arc-voltage gradient and the corresponding arc voltage changes by a factor of approximately 10.

The present invention, in part, is concerned with a fluid-blast circuit breaker, especially suitable for alternating-current interruptions, in which, as contrasted with known breakers, the interrupting work to be dissipated is considerably reduced. The present invention is, in part, distinguished by the fact that there is provided a control, which makes the quenching medium, serving for arc-extinguishing action in the case of arbitrary interruption times, effective only when the current is decreasing, specifically 0.5 to 2.0 milliseconds before the current passes through current zero.

The advantages of fluid-blast circuit breakers constructed in accordance with the present invention can be seen clearly from a comparison of FIGS. 1 and 2 of the drawings. In both figures i is the interrupted current, μ_b is the arc voltage, and t_b is the arcing time. The contact separation follows arbitrarily at instant t_0 . At instant t_1 there occurs the first passage of the current through current zero. However, the contact separation is still so small that the interruption of the arc does not

take place. At the instant t_3 the necessary separation distance is assumed to be reached and, therefore, the arc-quenching action should follow, whereby it is assumed that in both cases the maximum arc voltage μ_b occurs. Breakers of known design provide, shortly after the contact separation, immediately intensive arc-extinguishing action, which leads to increased arc voltage μ_b . On the contrary, in the case of circuit breakers constructed according to the present invention, intensive effect upon the arc can be found only in intervals t_0-t_1 and t_2-t_3 . The arc voltage will, therefore, remain very small in magnitude up to the instant t_2 and increase correspondingly only toward the passage through current zero t_3 . This results in that the interrupting work, represented by the shaded area A_2 , as illustrated in FIG. 2, is only a fraction of the interrupting work A_1 , as shown in FIG. 1, being approximately $\frac{1}{5}$ in the illustrated example taken from an actual case. In addition, there exists also a considerably lower maximum arc power $\dot{N}_2$, which amounts to approximately one-half of $\dot{N}_1$. Correspondingly, the stresses from pressure in the case of circuit breakers, constructed in accordance with the present invention, are considerably lower, which makes possible a lighter design of the interrupting chamber and leads consequently to lower production costs.

Still a further improvement can be obtained by constructing circuit breakers in accordance with the present invention in that the intensity of quenching can be made dependent upon the magnitude of rate of decrease of the interrupted current, that is $(-di/dt')$. As well known, the quenching intensity must be the greater the greater is the instantaneous rate of change of the interrupted current immediately before the passage through current zero, and the greater is the slope of the recovery voltage. The latter is generally given by the network conditions and the magnitude of the interrupted short-circuit current. For a higher short-circuit current and thereby for a higher rate of change of the short-circuit current, there corresponds most of the time also a higher slope of the recovery voltage, because the inductance of the oscillating circuit at higher short-circuit intensities is correspondingly lower. If also the intensity of arc quenching is made greater, the greater is the rate of decrease of the interrupted current, then it can be expected that the arc quenching takes place with less possible effort, and also lowest overvoltage over the entire current range from very small currents up to full short-circuit current intensities. As well known, for example, in disconnecting a transformer running at no-load, a very high overvoltage occurs, because the quenching intensity is very often too high relative to the small no-load current, for example, only 10 amperes. The arc then interrupts too soon, which results in an instantaneous release of the large amount of magnetic energy stored in the transformer under a stronger build-up of the overvoltage. In case of compressed-gas circuit breakers, a matching of the intensity of interrupting conditions to the slope of current shortly before passage through current zero has an additional advantage in that the consumption of compressed air at normal switching operations is considerably reduced.

FIG. 3 shows by way of example a form of construction of compressed-gas circuit interrupter constructed in accordance with the present invention. With reference to FIG. 3, the reference numeral 1 indicates an interrupting chamber in the form of an insulating cylinder. At the top, the interrupting chamber 1 supports the interrupting nozzle contact 2 having a terminal lead 3. The bottom of the insulating cylinder 1 is closed by a closure cap 4 having a second terminal lead 5. The reference numeral 6 indicates cooperable sliding contacts which carry the current from the terminal lead 5 to the movable contact rod 7. The compressed gas is brought into the interrupting chamber 1 through an electrically actuated

valve 8 and an insulating blast tube 9. The reference numeral 10 indicates a rotatable valve damper shown in the open position in FIG. 3. It is actuated by a moving coil or armature 11, which rotates in the field of an electromagnetic system 12 excited by the interrupting current, as set forth in the aforesaid United States patent application.

The reference numeral 13 denotes an operating cylinder, which is connected through a tube 14 with the insulating blast tube 9. A piston 15, movable within the operating cylinder 13, is acted upon by a compression spring 16. An insulating operating rod 18 is supported upon a pivot 17, and is coupled with the piston 15 through a driving link 19. The rod 18 is also connected with the movable contact rod 7 by means of a pivot pin 20. In the open-circuit position, shown by the dotted lines 7a, the insulating operating rod 18 is held by a rotatable latch 21 against the biasing action exerted by the compression spring 16.

The circuit interrupter, generally designated by the reference numeral 22 and set forth in FIG. 3, functions in the following manner: At an arbitrary instant t_0 the electromagnetically actuated valve 8 is assumed to be opened. This action results in exposing the piston 15 to the entering blast of compressed gas, which will cause the piston 15 to move downwardly against the biasing action exerted by the compression spring 16 until the movable contact rod 7 reaches the illustrated open position 7a of completed interruption. Now, if the current is increasing during this process, then an induced current will flow through the moving coil or armature 11, which will, together with the flux in the magnetic system 12, produce in the air gap a torque, which causes the rotatable valve damper 10 to turn to a closed position. In this connection, it is to be noted that the magnetic circuit 12 encompasses the main current path L_1 , L_2 and consequently has flux generated therein corresponding to the line current. As a result, if at first the compressed air cannot enter the interrupting chamber 1 to blast the arc, the arc 23 burns with a much lower arc voltage than would be the case otherwise. Now, if the main current begins to decrease, then the current induced in the moving coil 11 will change its sign as set forth in the aforesaid United States Patent 3,215,866. The torque is then reversed, and the valve damper 10 will now assume the illustrated open position. By utilization of saturation of the magnetic system 12, it can be obtained that the current induced in the moving coil 11 begins to flow 0.5 to 2 milliseconds before the passage of the current through current zero. Now, at this time the compressed air may enter the interrupting chamber 1 from the blast tube 9 and act intensively upon the arc 23a drawn within the nozzle 2, thereby bringing about interruption of the arc 23a and consequent circuit interruption.

If, on the contrary, a transformer operating at no-load should be disconnected, and if, as a result of build-up of overvoltage causing a short circuit shortly before the no-load current of the transformer passes through current zero, then the current immediately sharply increases. This results in the situation whereby the valve damper 10 will be instantly moved into the closed position by the moving coil 11, by which action the passage of the flowing gas upon the arc 23a is stopped. The arc has a high current intensity but a very low arcing voltage. Later, when the current again begins to decrease, the valve damper 10 will then open and the arc quenching action will follow.

If the valve damper 10 is supported upon the rotatable shaft 11a of the moving armature 11, then it can be obtained in a relatively simple manner that the valve damper 10 opens wider the more quickly the line current decreases toward current zero. As a result, it is possible to match or correlate the intensity of quenching to the intensity of the interrupted current, especially to

the slope with which it passes through current zero. For this purpose, it may be suitable to establish the normal "at rest" position of the valve damper 10 in such a position that the minimum intensity of quenching, necessary for interruption of currents in the normal operating range, is provided. If now higher currents are to be interrupted, then automatically a correspondingly larger movement of the valve damper 10 takes place, so that again the intensity of quenching is adjusted to the prevailing conditions.

If, for example, in the case of interrupters using liquids, an expansion should be introduced, then blocking of a valve 10 during increasing current can be released when the current begins to decrease toward current zero, in which case it may be suitable to introduce the expansion shortly before the passage of the current through current zero.

The advantage of circuit breakers constructed according to the present invention consists largely in that the breaker mechanism itself can be built in the generally conventional manner, and does not need to move especially fast as is necessary in the case of conventional synchronized breakers. The control is limited entirely to the matching or correlating of the intensity of interrupting action to the prevailing conditions, which can be done at a small cost. The interrupting capacity of breakers of the type built according to the present invention can be, although at approximately the same production cost as conventional breakers, increased to several times the value so far obtained.

It is known in the valve art to provide arrangements including a rotatable wind-type valve adapted to be electrically operated and disposed within a cylindrical opening. With valves of this type it is desirable that the valve, when closed, have a very tight fit and, when opened, permit optimum flow conditions to take place. Opening of such valves is usually effected by rotating the valve about 90°. The electrical drive may comprise either a motor or a magnetic drive. If it is desired to provide valves which have a short operating time from closed condition to open condition, or vice versa, of less than $\frac{1}{100}$ of a second particularly less than one millisecond, certain problems are encountered at once. Such extremely fast-acting valves are needed, for example, for compressed-fluid electrical switches in which arc extinction is effected by a flowing medium. In such switches, or circuit breakers it is necessary that the valves be operated, for example, at a certain instant, within one current half-cycle. It is not absolutely necessary in circuit breakers for the valve to establish a perfect seal when closed, for a small amount of leakage is not objectionable since the quick-acting valve usually has connected in series therewith another tightly-closed valve, such as indicated by the reference numeral 27 in FIG. 4, which may be of conventional design.

According to one aspect of the present invention as shown in FIGS. 4 and 5, the valve arrangement including at least one electrically-operated rotatable wing valve disposed in a cylindrical opening is characterized in that the cross-section of the rotary wing, or wings perpendicular to the axis of rotation is biangular for obtaining opening and closing times of less than 10 milliseconds, the width "b" of the axial sealing surfaces of the rotatable wing amounting to only a fraction of the maximum wing thickness "d", and the width of the rectangular valve opening B being no more than equal to the radius "r" of the rotatable wing.

In FIGS. 4 and 5 of the drawings, a valve arrangement, according to the invention, is shown schematically in the closed and open positions, respectively. FIGS. 6 and 7 illustrate a similar valve arrangement which offers particularly little resistance to flow, and FIG. 8 shows a double valve arrangement including two rotatable wing valves actuated by a single moving-coil system.

In FIGS. 4 and 5, the reference numeral 31 designates

a cylindrical valve casing and the reference numeral 32 indicates the wing-valve comprising two plates 33 and 34 rigidly connected to the shaft 35. The axial sealing surfaces are indicated at 36. The reference numeral 37 designates rectangular inlet, and the reference numeral 38 designates the rectangular outlet. In FIG. 4 of the drawings, the pressure P acts upon the upper surface 33 of the rotatable wing valve 32. Since the pressure distribution relative to the axis of rotation 35 is symmetrical, substantially no resultant torque is applied to the wing-valve 32.

FIG. 5 shows the valve in its fully opened position, and this figure also illustrates the fact that the torsional moment, or torque acting upon the wing valve 32 is zero. Contrary to the positioning of the valve 32 shown in FIG. 4 in which there exists a stable equilibrium, the equilibrium in the open position, as shown in FIG. 5 is unstable. As soon as the wing valve is moved somewhat from its symmetrical position, it tends to move to its closed position, and the maximum closing force is effective approximately in the position indicated by broken lines 32a in FIG. 5. Accurate measurements taken with the valve arrangement according to FIG. 4 and involving the values $r=6$ millimeters, $B=5$ millimeters, $d=3$ millimeters, and a wing height of 30 millimeters indicated at 1 to 6 atmospheres over-pressure on the inlet side, result in a maximum torque in the closing direction of about 80 pond (gram weight) centimeters, that is, an extraordinarily small value which, however, is obtainable only when ball bearings are being used.

The width of the axial sealing surface of the rotatable wing valve was $b=1.2$ millimeters, and the sealing gap amounted to about $\frac{1}{100}$ millimeter. The resultant leakage loss at 6 atmospheres was $2 \text{ cm}^3/\text{ms}$. relative to normal pressure and normal temperature. With a gap thickness of $\frac{1}{100}$ millimeter, it was possible to reduce the leakage loss to $0.9 \text{ cm}^3/\text{ms}$. Sealing can further be improved by providing at least along the axial sealing surfaces of the rotatable wing sealing strips, which are biased outwardly, such as used, for example in rotary-piston type motors.

The embodiment illustrated in FIGS. 4 and 5 of the drawings has the following advantages: The moment of inertia of the rotatable wing valve 32 is very small. Despite this, however, the stability is high due to the box-type construction. In order to fully open the valve, an angular movement of the wing only of $\alpha/2$ is required. The torque necessary to move the rotatable wing is very small. The resistance to flow of the opened valve is negligible. The use of wings having a height which is substantially larger than their diameter makes it possible to obtain large cross-sectional flow areas with valves of minimum dimensions.

FIGS. 6 and 7 illustrate an embodiment of the invention providing a valve arrangement for still better flow conditions. The rotatable wing 42, which is movable within the casing 41 has an air-foil or streamlined profile. It may be formed, together with the shaft 43, by die-casting, for example, from an aluminum or magnesium alloy, the moment of inertia being further reduced by the axial openings 44. Furthermore, the casing 41 may have disposed therein liners 45 and 46, as shown in FIG. 7, which are favorable to the streamline flow of the medium.

FIG. 8 shows an embodiment of the invention utilizing valves 51 and 52 of the type illustrated in FIGS. 4 and 5. Valve 51 is shown in its open position, whereas valve 52 is shown in its closed position. Indicated generally at 53 is a moving-coil system, the moving coil 54 of which is secured to the common shaft 55. The coil ends of coil 54 extend to the slip rings 56 and 57 and are connected through brushes 58 and 59 and a switch 60 to a battery 61. The pole pieces of the moving-coil system are indicated at 62 and 63.

As the double throw switch 60 is moved from the

center position, indicated by broken lines, to the upper position, current will flow through coil 54 in the direction indicated by the arrow, said current, together with the air-gap induction producing a torque which causes the valve 51 to be moved to its closed position and valve 52 to be moved to its open position.

Referring to FIG. 8, the rotary wing of valve 51 tends to move clockwise to its closed position, whereas the rotary wing of valve 52 tends to move counter-clockwise also to its closed position, as shown. It is, therefore, apparent that the two torques of the rotary wings 51, 52 substantially cancel each other. Movement of switch 60 to its lower position effects a reversal of the current flowing through coil 54, which, in turn, also reverses the torque. Thus, the two rotary wings of valves 51 and 52 return to the position shown.

Tests have proven that with an arrangement such as shown in FIG. 8, it is readily possible to effect movement through the angle $\alpha/2$ (FIG. 4) in less than 1 millisecond. The moment of inertia of one rotary wing including the shaft amounts to only about 10% of the moment of inertia of the moving coil 54.

In one practical example, the main driving torque of the moving-coil system amounted to approximately 12 kpcm., whereas the resultant maximum counter-torque acting upon the rotary wings amounted to only about 0.03 kpcm., that is, to only 2.5% of the driving torque, at 6 atmospheres of over-pressure.

The battery 61 may be replaced by a charged condenser, which, when discharged, causes a very high impulse-like current to flow through the moving coil 54. Furthermore, the permanent magnet system 62 and 63 may be replaced by an unsaturated, or saturated alternating-current magnet. If this is the case, and if coil 54 is supplied from a source of direct current, the rotary wings will oscillate at the frequency of the alternating current.

If it is desired to use the valve arrangement according to the invention for the control of fluid-blast circuit breakers, it is desirable to energize the magnetic system 62 and 63 in dependency upon the current to be interrupted, whereas the moving coil 54 should be supplied with a current which may be proportional, for example, to the changing rate of the current to be interrupted. In this manner, it is possible to cause valve 51 to open only when the current decreases, particularly shortly before the zero passage of the current, and to be closed during the increase of the current, during which period the circuit breaker is vented by the valve 52, as illustrated in FIG. 10, hereinafter described. In view of the extraordinarily short response time of these valves 51 and 52, the valve arrangement embodying the invention may be used advantageously in connection with control and regulating systems.

In circuit-breaker techniques there exists a common tendency to emphasize the time characteristic of the switching device. This is especially of importance when the switching operation should take place at a definite instant within a half-cycle of the alternating current, or near the passing through current zero in the case of a D.C. reversing current, as it may be required for synchronized breakers, high-speed breakers, regulating equipment, and rectifiers. Up to now, the high-voltage breaker devices were generally built with tulip-shaped, or nozzle-like stationary contacts and movable contact pins. However, there are also known designs in which a nozzle is moved axially to obtain the interruption. All of these designs involve a large mass of movable parts, especially for current ratings over 400 amperes.

An aspect of the present invention covers an electrical switching device operated by compressed medium, with one stationary and one movable contact system, which is subjected to opposing forces. The above-mentioned disadvantages are avoided in that the stationary contact system has at least two electrodes, and at least one of these

has a nozzle-like shape. Preferably the stationary contact system is surrounded by an electrically insulating shell, inside of which is arranged the movable contact system, whereby for interruption there is provided inside of the shell a pressure by which the movable contact system is brought into the open position, and that the stationary contact system is arranged so that the interrupting arc, which is drawn when the contacts are separated, is driven into the nozzle opening and extinguished.

FIGS. 9 and 10 generally describe examples of two forms of compressed gas circuit-breaker arrangements constructed in accordance with the present invention. FIG. 9 is a composite view with FIG. 9A illustrating the breaker in the closed-circuit position, whereas FIG. 9B illustrates the breaker during the opening operation with arcing being established. FIG. 11 shows a special form of design of the stationary contact system.

In FIG. 9, the reference numeral 81 indicates a conducting nozzle having an orifice opening 82, opposite to which is arranged another conducting nozzle 83 having a smaller orifice opening 84. The conducting nozzle 81 is connected with a spider piece 85 which supports the upper terminal lead 86 and the arcing electrode 87 of the interrupter. The nozzle 83 is connected with a spider member 88, which supports the lower terminal lead 89 and the arcing electrode 90. The reference numeral 91 indicates movable contact segments arranged peripherally along the outer circumference of the conducting nozzles. They are connected to pistons 92 and are pressed against the conducting nozzles 81 and 83 by compression springs 93. The operating cylinders 94 in the insulating chamber 95, in which the pistons 92 are moving, are closed by a threaded cover 96. The contacts 91 and the pistons 92 are interconnected by operating rods 97 having hook-shaped portions 98, which, in the open position, engage under angular latches 99, whereby the segmental movable contacts 91 are held in the open-circuit position.

At the outer side of the nozzle 81 there is arranged an insulating exhaust casing 100 which is widened toward its upper end, and which is closed by a perforated cover 101. An inlet 102 is provided for the medium being held under pressure. For cooling and noise suppression purposes the space 103 may be filled with various cooling devices, such as screening, concentric metallic tubes, or the like (not shown).

The opening operation of the compressed-gas circuit interrupter 80 of FIG. 9 is as follows: When the valve 104 is opened, the medium, such as gas held under pressure, flows through the opening 102 into the interrupting chamber 95. As a result, the movable pistons 92 and with them the movable segmental contacts 91 are forced radially outwardly toward the outside of the interrupting chamber 95 against the action exerted by the compression springs 93. This action happens very quickly due to the small moving masses. The short arcs 105 and 106 (FIG. 9B) terminate on the contacts 91 as they are being opened, and are immediately driven inwardly along the nozzle surfaces 107, 108 by the inwardly directed flow of the quenching medium. This action is augmented by the electrodynamic forces present. The merged arc 109, terminating between the arcing electrodes 87 and 90, is extinguished by the axially-flowing gas blast. The hook portions 98 secured to the guide rods 97 of the contacts 91 are held in the open-circuit position by the latches 99, as illustrated in FIG. 9B of the drawings. This concludes the opening operation of the interrupter 80.

For initiating the closing operation, the latches 99 are withdrawn by a control device, not shown in the figure. The result of this is that the contact pieces 91 move back into the closed position, as shown in FIG. 9A, under the biasing force of the compression springs 93. The valve 104 is purposely controlled by a synchronous operator in accordance with the teaching of the aforesaid patent application Serial No. 97,656 so that the flow of the compressed medium starts only when the current is de-

ing, specifically shortly before the passage of the current through the zero value.

The control valve 104 is opened during descending values of the instantaneous current i_1 being interrupted in accordance with the teaching of the aforesaid patent application Serial No. 97,656. The synchronous operator 110 includes a magnetic circuit 111 and a moving coil system, or armature 112. The moving coil system 112 includes a moving coil 113 comprising a winding closed upon itself and may consist of a rectangular copper or aluminum frame. The magnetic circuit 111 is energized by the current i_1 to be interrupted. The current i_1 sets up a magnetic field in the magnetic circuit 111, which induces a current i_2 in the closed frame 113. The flux Φ_s causes an induction B_s in the air gap 114. The magnetic circuit 111 becomes saturated during peak instantaneous values of the short-circuit current i_1 . Near a current zero on the descending part of the current wave the core 111 unsaturates, Φ_s decreases rapidly in value inducing i_2 , and a torque is created at this time in the control shaft 115 opening the valve 104. Reference may be had to FIG. 3 of the aforesaid application for a detailed discussion of the theory of operation. The small opening 84 in the nozzle 83 has particularly the function to remove the formed metallic vapors to the lower part of the interrupting chamber whereby a subsequent opening operation is substantially improved without the air consumption being noticeably increased.

FIG. 10 shows another form of compressed-gas breaker design according to the present invention including the circulation of the compressed medium and an additional interrupting gap. The nozzle-like stationary contacts 119, 120 are connected to spider members 121 and 122. The upper terminal lead is designated by the reference numeral 123. A contact extension 124 is slidably connected with a movable contact cluster 125, which in the closed position, provides a contact with a lower terminal lead 126. The movable contact finger assembly 125 is moved up or down by means of a pivotally mounted insulating lever 127 which is held in an elastomeric sleeve 128, such as synthetic rubber.

The movable segmental contacts 129 are mounted on the inner surface of an elastomeric, or rubber-like sleeve member 130, which provides the desired contact pressure between the movable contacts 129 and the relatively stationary contacts 119, 120. The reference numeral 131 designates a rotary double-damper valve operating according to the description of the invention pertaining to FIG. 8 of the drawings through which the quenching medium flows from a high-pressure tank 132 through the valve 51 and enters into the space formed by the rubber sleeve 130, while the reference numeral 52 indicating a corresponding companion rotary damper valve, which is connected to the low-pressure tank 133 and which, when opened, provides the discharge from the arcing chamber 134.

The interrupting gases are exhausted from the nozzle openings 135, 136 and can escape through the openings into the low-pressure space. The entire interrupting space is enclosed by an insulating container 138 with end closer caps 139 and 140. In the case of compressed-gas breakers, a low pressure of say 2.5 to 7.5 atmospheres, for example depending upon the operating voltage, can be used, while the high pressure can be set suitably to approximately 6 to 12 atmospheres, for example. A compressor, not shown, can be provided between the low-pressure tank 133 and the concentric high-pressure tank 132. The high pressure tank 132 is tightly sealed off from the rotary damper valve 131, and thus from the inside of the insulating cylinder 138 by a conventional series blast valve 27. By means of a magnet system 141, shown by the dotted lines, which acts upon a moving coil 53 it can be arranged that the damper valve 51 opens only when the current is decreasing, especially shortly before the current passes through its current-zero value.

FIG. 11 shows in vertical section and FIG. 12 in a hori-

zontal view of a modified form of the lower nozzle-like electrode 120a with especially strong electrodynamic effect upon the arc. The stationary contact 120a is provided with radial slits 142. For improvement of flow distribution, inside of the contact there is arranged an insulating flow piece 143, which opens downwardly and which for the purpose of guiding the arc, extends somewhat beyond the slits 142. Should an arc start, for example at point 144, then due to the dynamic force affecting the current loop, this arc will be moved along the dotted line toward the nozzle opening 145 and extinguished with a greater speed.

The breaker arrangement illustrated in FIGS. 10-12 operates in the following manner: The interruption of the current is started by opening the valve 27 at any assumed time. Up to heavy overcurrents the damper valve 51 maintains the illustrated open position. The compressed gas enters the inside of the rubber sleeve 130, and inflates it, whereby the movable contacts 129 are moved away from the nozzles 119 and 120. The arcs, appearing at the opening of the contacts 129, are driven inside and are quenched in the nozzle system. At higher overcurrents, and especially at short-circuit currents, valve 27 will be opened, for example, by the respective overcurrent or protective relay or by selective operation in which case it is of advantage to take such measures, that the opening of valve 27 is possible only when the current is increasing. The damper valve 51 is then at first in the closed position and is opened by the action of the magnetic system 141 and the moving coil 53 only when the current is decreasing, whereby the damper valve 52 is immediately closed. The interruption of the current then follows in the described manner. With a certain amount of time lag, although before closing of the valve 27, the movable contact finger assembly 125 is moved upwards by the rod 127 so that an open isolating gap appears between the contact cluster 125 and the upper end of the lead 126. After the valve 27 has been closed, the inside space of the rubber sleeve 130 is exhausted. This results in that the movable contacts 129 may move back into the illustrated closed position. The closing of the circuit is subsequently achieved by moving the contact cluster 125 downwards into the position as shown in FIG. 10.

Should it happen, that the arc does not go out, then the moving coil 53, immediately after the current passes through current zero, turns in the opposite direction, causing thereby the damper valve 51 to close and the damper valve 52 to open. This results in immediate release of pressure inside of the rubber sleeve 130. The movable contacts 129 move into the closed position, the arc is short-circuited and is extinguished. As soon as the current again begins to decrease, the above-described interrupting process is repeated.

In order to increase the speed of interruption it can be of advantage to provide reinforcing segments 146 on the rubber sleeve 130. If these segments are solidly connected with the rubber hose, for example, by vulcanizing, then the elastic constant and consequently, also the contact pressure in the closed position are increased.

Switching arrangements according to this invention have significant advantages. The quenching system proper, consisting of a simple, asymmetrical or symmetrical double nozzle, due to favorable distribution of the electric field and optimum flow distribution, results in excellent quenching effectiveness. Through application of constant static relatively low pressure inside of the system, a higher dielectric strength in the open position can be obtained despite a smaller open gap. The adaptation to higher voltages can be obtained in a simple manner by increasing the static pressure inside of the chamber 134 so that it is possible, for example, with the very same chamber, to build breakers from 6 to 30 kv., which has considerable advantages with respect to manufacturing cost and stock maintenance.

The dimensions of the chamber 134 itself can be held

small, especially when a synchronized control is provided. In case of designs with gas circulation the usual annoying, explosion-like noise of compressed-gas breakers is completely suppressed. With respect to their quenching effectiveness and higher dielectric strength, also some especially suitable gases can be used, such as carbon dioxide CO_2 , electro-negative gases, for example sulfur-hexafluoride gas SF_6 . But it is also possible to operate the breakers according to this invention with insulating liquids, which are forced in a suitable manner through the nozzle openings. Also in this case it is possible and recommended to use synchronized control in which the flow of quenching medium is started only when the current is decreasing, especially shortly before it is passing through zero, which is of special advantage because of consequent small interrupting work and, therefore, practically eliminated back-pressure.

The total mass of the movable contacts 129 can be held very low also at high-rated currents (1000 amps. and more). For example, the weight of one of the eight movable contact pieces of a 1250 amp. breaker amounts to only 1.5 pond (gram weight) while the breaker can interrupt a symmetrical short circuit current of 30 kiloamperes and a momentary short circuit current of 70 kiloamperes which corresponds to interrupting capacity of 500 mva. at 10 kv., or 1500 mva. at 30 kv. Due to these extremely small masses, the acceleration of the movable contacts can reach 5000 g. and more. Because, due to the static gas pressure or to the insulating liquid utilized, and the application of double interrupting gaps, only small gaps of a few millimeters are necessary, the interrupting time of a fraction of one millisecond is obtainable. If there is arranged an additional interrupting gap, in series with the main interrupting system, then in the open position the voltage stress falls essentially on this second interrupting gap. This makes it possible to reduce some more the striking distance of the main interrupting gap and, therefore, the interrupting time. If the additional interrupting gap is built at the same time also for interrupting of smaller switching loads, then a resistance 148 (See FIG. 10) can be connected in parallel to the main interrupting gap, whereby the rise of recovery voltage is reduced, and the interrupting capacity is correspondingly increased.

Although there have been illustrated and described specific structures, it is to be clearly understood that the same were merely for the purpose of illustration, and that changes and modifications may readily be made therein by those skilled in the art, without departing from the spirit and scope of the invention.

I claim as my invention:

1. The combination in a fluid blast circuit interrupter of a pair of spaced relatively fixed nozzle-shaped contacts, a plurality of movable bridging segmental contacts for bridging said pair of spaced relatively fixed nozzle-shaped contacts in the closed circuit position of the interrupter, each of said segmental bridging contacts having a piston member secured thereto, blast valve means including a synchronous operator for releasing a blast of compressed fluid into the circuit interrupter for acting upon the several piston members for effecting arc establishment, means for directing the fluid blast radially inwardly toward the nozzle openings of said pair of relatively fixed nozzle-shaped contacts, said synchronous operator being effective to cause blast valve opening only near a current zero on the descending part of the current wave, and a pair of spaced relatively fixed arcing electrodes disposed along the axis of the nozzle-shaped contacts for positioning the arc axially along the nozzle-shaped openings of the contacts.

2. The combination in a fluid blast circuit interrupter of a pair of spaced relatively fixed nozzle-shaped contacts, a plurality of movable bridging segmental contacts for bridging said pair of spaced relatively fixed nozzle-shaped contacts in the closed circuit position of the interrupter,

each of said segmental bridging contacts having a piston member secured thereto, blast valve means including a synchronous operator for releasing a blast of compressed fluid into the circuit interrupter for acting upon the several piston members for effecting arc establishment, means for directing the fluid blast radially inwardly toward the nozzle openings of said pair of relatively fixed nozzle-shaped contacts, said synchronous operator being effective to cause blast valve opening only near a current zero on the descending part of the current wave, a pair of spaced relatively fixed arcing electrodes disposed along the axis of the nozzle-shaped contacts for positioning the arc axially along the nozzle-shaped openings of the contacts, and latching means for latching the piston members in the open circuit position for effecting circuit isolation.

3. A compressed-gas circuit interrupter including a pair of cooperable relatively fixed nozzle-shaped contacts, a resilient rubber-like sleeve carrying one or more segmental movable bridging contacts for bridging said pair of cooperable contacts in the closed circuit position, blast-valve means including a synchronous operator for effecting a blast of gas within said rubber-like sleeve only near a current zero on the descending part of a fault-current wave, whereby said one or more segmental contacts will draw arcs only near a current zero on the alternating current wave.

4. A circulating-system type of compressed-gas circuit interrupter including means defining a high-pressure storage tank, a relatively low-pressure storage tank, a pair of cooperable relatively fixed nozzle-shaped contacts, a resilient rubber-like sleeve carrying one or more segmental movable bridging contacts for bridging said pair of cooperable contacts in the closed circuit position, blast-valve means including a synchronous operator for effecting a blast of gas within said rubber-like sleeve only near a current zero on the descending part of a fault-current wave, whereby said one or more segmental contacts will draw arcs only near a current zero on the alternating current wave.

5. The combination in a compressed-gas circuit interrupter of means defining a high-pressure chamber, means defining a low pressure chamber, conduit means including a double-damper synchronous valve and an interrupting chamber interconnecting the two chambers, a synchronous operator for actuating said valve on the descending portion of the current wave, a pair of cooperable relatively fixed nozzle-shaped contacts, a resilient rubber-like sleeve carrying one or more segmental movable bridging contacts for bridging said pair of cooperable contacts in the closed circuit position, whereby the arc will be drawn only near a current zero on the descending part of the fault current wave.

6. The compressed-gas circuit interrupter according to claim 5, wherein the double-damper valve includes an open damper valve and a closed damper valve.

7. A fluid-blast circuit interrupter including a nozzle-shaped contact having radial slots thereon, insulating means disposed within said slots, means including a cooperable contact for establishing an arc terminating on said nozzle-shaped contact, and means causing a radially inwardly directed fluid blast to blast through said nozzle-shaped contact to effect extinction of said arc.

8. A fluid-blast circuit interrupter including a relatively stationary contact structure comprising a spaced cooperable pair of nozzle-shaped contacts having fluid-exhausting orifice openings therein, a surrounding insulating flexible shell composed of an elastomeric material, one or more bridging contact segments secured to and carried by the inner wall of said elastomeric shell, blast-valve means, means storing fluid under pressure, and opening of said blast-valve means releasing a blast of high-pressure fluid interiorly within said shell to effect disengagement of said one or more bridging contact segments by outward bridging deformation of the shell.

13

9. The fluid-blast circuit interrupter according to claim 8, wherein means direct said fluid-blast radially inwardly between the spaced relatively stationary nozzle-shaped contacts and axially outwardly through said exhausting orifices.

10. The fluid-blast circuit interrupter according to claim 8, wherein said blast-valve means includes a series control valve and a butterfly valve actuated by a synchronous operator.

11. The fluid-blast circuit interrupter according to claim 8, wherein said blast-valve means includes a double-

14

damper valve, a synchronous operator and a series control valve.
